UNITED STATES PATENT OFFICE.

CHARLES B. GARRETT, OF CINCINNATI, OHIO, ASSIGNOR TO THE GLOBE AUTOMATIC SPRINKLER COMPANY, OF PHILADELPHIA, PENNSYLVANIA, A CORPORATION OF PENNSYLVANIA.

DRY-PIPE VALVE.

1,197,282.

Specification of Letters Patent. Patented Sept. 5, 1916.

Application filed June 12, 1916. Serial No. 103,087.

To all whom it may concern:

Be it known that I, CHARLES B. GARRETT, a citizen of the United States, and residing at Cincinnati, in the county of Hamilton and State of Ohio, have invented a new and useful Improvement in Dry-Pipe Valves, of which the following specification is a full disclosure.

My invention relates to fire extinguishing systems and in particular to a valve designated as an auxiliary dry pipe valve connecting with the sprinkler lines leading to isolated portions, which are not protected against frost for establishing a dry system in such lines. In such dry pipe sections of the system the valve is normally retained in closed position against a water supply pressure by a lesser degree of air pressure within such dry pipe sections and the valve automatically opens on a decrease of pressure below a determined degree primarily due to the opening of one or more of the sprinkler heads connecting or controlling the dry line sections. A differential valve is employed which is of smaller size with the weight of the clapper insufficient to insure a proper sealing of the valve for retaining the priming charge of water required when applying the air pressure in setting. Therefore it is necessary to apply additional pressure on the clapper which I accomplish by providing a latch member connecting with the valve or its clapper, and resistingly engaging a rigid abutment for superimposing a pressure on the valve, the latch member additionally functioned to hold the valve open after it is tripped, making manual resetting compulsory.

The object of the invention is to provide a valve for dry pipe sprinkler lines with means for exerting a seating pressure against the valve for priming, releasing under prevailing pressure upon the opposite side of the valve, and said means also serving as a latch for holding the valve open when tripped, preventing automatic reseating of the valve.

Another object is to provide means for normally exerting a positive seating pressure on the valve mechanism independent of the air pressure within the system.

Other objects of the invention will be more fully set forth in the description of

the accompanying drawings, forming a part of this specification, in which:—

Figure 1 is an elevation of the control devices of the system showing the dry-pipe valve in section, its valve mechanism being in normal set position. Fig. 2 is a similar section of the dry-pipe valve showing the valve mechanism in partly open position, the latch preventing a reseating thereof. Fig. 3 is a semi-diagrammatic view showing a portion of the valve and the automatic ball-drip in section.

The term "dry-pipe valve" herein refers to the structure as a unit, the valve proper being hereinafter referred to as the differential valve because of the differential valve areas normally exposed to the opposing pressures.

Referring to the drawings, the "dry-pipe valve" comprises a two-part casing, the base member 1 having at its lower end an inlet opening 2 communicating with the water supply pipe 3 and provided with an outlet opening 4 communicating with the distributing pipes of the sprinkler system through the main stand pipe or riser, which is illustrated at 5. The upper casing member 6 serves as a closure for the base member 1 and when removed provides full accessibility to the valve parts for setting and cleaning. The inlet opening or passage 2 is provided with a valve seat 7 of approximately the same diameter as the supply pipe 3, adapted for coöperation with a depending valve annulus 8 of a differential valve plate 9 and forming a main valve for closing the water supply pipe. The valve plate 9 has secured to its circumferential edge, by an annular ring 10 and screws 11, a flexible annular ring 12 coöperating with an annular valve seat 13, concentric with the valve seat 7 but of larger diameter, forming an auxiliary or secondary valve.

When the differential valve is in normal position, as shown in Fig. 1, and the valve chamber containing priming water to form a water seal, the system is filled with compressed air of sufficient pressure to retain the valve in closed position against the water pressure in the supply pipe. The difference in diameter between the upper surface of the valve plate 9 exposed to the system air pressure and the under surface sub-

jected to the water supply pressure, enables a relatively small degree of air pressure to withstand a much greater degree of water supply pressure. The valve plate 9 is pivoted on a rocker arm 14 journaled on a pivot pin 15 and provided with projections 16 extending adjacent the upper surface of the valve plate, so that only a slight rocking movement thereof is permitted to enable a perfect seating of the valves.

When the differential valve is caused to open by a decrease in the system air pressure below a predetermined minimum, the rapid inrush of water will, by its acquired momentum, increase the pressure of the air within the system to such a degree as to create a back pressure and cause a reseating of the valve on its seat and unless means are provided for preventing this automatic reseating of the valve after it is once opened, a condition known in the art as "water column" will result. This condition is due to the recession of the column of water in the system, caused by the reaction of the air pocketed in various inactive sprinkler lines of the system, such recession, by reason of the differential area of the valve, causing the valve to reseat. To overcome this possible condition, I provide a latch 17 which is pivotally mounted on the end of the rocker arm 14 and is urged against a stop pin 18, secured to the casing, by a leaf spring 19, one end of which is secured to said arm and the other end of which engages the upper end of the latch. This latch has a hooked nose 20, which, when the differential valve is raised a short distance, engages over the top of the stop pin to prevent an automatic reseating of the valve. A stop abutment 21 extends downwardly from the handhole cover plate 6 and serves to limit the opening movement of the valve and prevents a possible injury of the latch mechanism. This latch mechanism renders it necessary to manually reseat the valve after first removing the hand-hole cover plate 6; thereby rendering it compulsory to first drain the system.

In priming the system previous to the introduction of the compressed air, it is necessary that the differential valve be firmly seated to prevent an escape of the priming water and as the weight of the valve plate 9 and rocker arm 14 is insufficient to insure a tight valve joint, additional pressure must be applied. This is provided for by the spring 19 and the particular formation of the abutting surfaces of the latch 17 and stop pin 18. As shown, the stop pin 18 has a beveled surface 22 and the nose 20, of the latch 17, has a correspondingly beveled surface 23, both coöperating under the influence of the spring 19 to exert a downward pressure on the rocker arm 14 and valve plate 10, through the latch 17. In this instance, the pin acts as an abutment

to prevent an independent swinging of the latch and any other form of abutment, such as a ledge projecting from the casing would be as efficient. Also, it would be as efficient if only one of the abutting surfaces were beveled. In the present instance the beveled pin is shown as a detachable element. This is a preferred form adapted for convenience in machining and assembling.

Intermediate the two valve seats 7 and 13 is a drip chamber 30, into which any accidental leakage past the valves will normally flow. This chamber normally is in free communication with the atmosphere through a drip conduit 31 leading to a drip cup 32 as a part of the drain pipe line. The drip conduit is provided with a ball valve 33 adapted to operate to close the conduit when the differential valve is opened. Means are provided for connecting to the conduit at 34, a pressure operated alarm or electric circuit control for alarm purposes, if desired. When the service valve 25 is closed and the system drained, the ball valve immediately opens to drain the water remaining in the valve chamber below the level of the outlet opening.

The valve mechanism is set or reset after first draining the system, a valve controlled drain pipe 24 communicating with the stand pipe 5, being provided for this purpose, it, of course, being obvious that the water supply has previously been cut off by closing the service valve 25.

After the system is drained, the custodian may remove the hand-hole cover and clean and reset the valve mechanism, subsequently replacing the cover. Priming water is then supplied through the valve controlled priming line 26, the latch spring 19, through the coöperation of the beveled surfaces of the latch nose 20 and stop pin 18, applying sufficient pressure to the differential valve to insure a tight valve joint. Compressed air is then introduced through the valve controlled air line 27 and the system is then completely normalized for subsequent operation.

Having described my invention, I claim:

1. A dry pipe valve comprising a casing forming a valve chamber having inlet and outlet openings, the casing being provided with a projecting abutment, a valve controlling the inlet opening held closed or lifted by variations in the relative pressure of either side of said valve, and means carried by the valve and adapted to engage the abutment to exert a seating pressure on the valve.

2. A dry pipe valve comprising a casing forming a valve chamber having inlet and outlet openings, the casing being provided with a projecting abutment, a valve controlling the inlet opening held closed or lifted by variations in the relative pressure

of either side of said valve, means carried by the valve and adapted to engage the abutment to exert a positive independent closing pressure on the valve, and means preventing an automatic reseating of the valve.

3. A dry pipe valve comprising a valve chamber having inlet and outlet openings, the casing being provided with a projecting abutment, a valve controlling the inlet opening held closed or lifted by variations in the relative pressure on either side of said valve, a latch carried by the valve, and means forcing the latch into engagement with the abutment to normally exert an independent closing pressure on the valve and subsequently to shift the latch into intercepting alignment with the abutment to prevent an automatic reseating of the valve.

4. A dry pipe valve comprising a casing forming a valve chamber having inlet and outlet openings, the casing being provided with a projecting abutment, a rocker arm journaled within the valve chamber, a valve controlling the inlet opening, carried by the rocker arm and held closed or lifted by variations in the relative pressure on either side of said valve, a latch pivoted on the free end of said arm, and means forcing the latch into engagement with the abutment to normally exert an independent closing pressure on the valve and subsequently to shift the latch into intercepting alignment with the abutment to prevent an automatic reseating of the valve.

5. A dry pipe valve comprising a casing forming a valve chamber having inlet and outlet openings, the casing being provided with a projecting abutment having a beveled surface, a valve controlling the inlet opening, held closed or open by variations in the relative pressure on either side of said valve, a latch carried by the valve, means forcing the latch into engagement with the beveled abutment surface to normally exert an independent closing pressure on the valve and subsequently to shift the latch into intercepting alignment with the abutment projection to prevent an automatic reseating of the valve.

6. A dry pipe valve comprising a casing forming a valve chamber having inlet and outlet openings, the casing being provided with a projecting abutment having a beveled surface, a rocker arm journaled within the valve chamber, a valve controlling the inlet opening, carried by the rocker arm and held

closed or lifted by variations in the relative pressure on either side of the valve, a latch pivoted to the free end of the rocker arm, and means forcing the latch into engagement with the beveled abutment surface to normally exert an independent closing pressure on the arm and valve, and subsequently shift said latch into intercepting alignment with the abutment projection to prevent an automatic reseating of the valve.

7. A valve of the character described comprising a bisected casing providing a base portion and a removable closure portion, said base portion having a valve seat 70 equipped inlet opening and an outlet port, a hinged valve swinging to engage with the seat of said opening, and a latch member connected with said valve and adapted to be releasably confined within said base portion of said casing for imposing a seating pressure on said valve.

8. A valve of the character described comprising a casing having a valve-seat equipped opening, and an outlet port, a valve hinged to close said opening, a member connecting with said valve, adapted to engage a rigid abutment within the casing confiningly seating the valve and releasable under a determined pressure imposed upon 85 the opposite side of the valve, and lockingly engaging with said abutment to hold the valve open after tripping said valve.

9. In a dry pipe valve, the combination of a valve casing forming part of the conduit 90 of a fire extinguishing system, a valve therein, adapted to control the passage of fluids therethrough, and means incorporated with said valve to hold it closed independent of fluid or air pressure, said means adapted to 95 prevent the valve closing after it has once opened.

10. A dry pipe valve comprising a casing forming a valve chamber, a valve therein controlling the passage of fluid through 100 said chamber, and mechanical means normally exerting an independent closing pressure on the valve and automatically operative to prevent an automatic reseating of the valve.

In witness whereof, I hereunto subscribe my name, as attested by the two subscribing witnesses.

CHARLES B. GARRETT.
